Albert W. Metzner

ATTORNEYS.

UNITED STATES PATENT OFFICE.

ALBERT W. METZNER, OF DAYTON, OHIO, ASSIGNOR TO JOHN Q. SHERMAN, OF DAYTON, OHIO.

PRINTING-PLATE-MOUNTING DEVICE.

Application filed December 21, 1921. Serial No. 523,807.

My invention relates to devices for serving as an accurate guide and, in addition, as a temporary clamp in connection with the mounting of printing plates in chases, 5 mounting boards or blocks.

While my invention has a wider application, I have designed it particularly for use in making up a chase from type plates for printing manifolding forms.

10 In such printing it is the general practice to print on a wide web of paper, two or more copies of a form, side by side, so that when the paper is split along the dividing line between the form, there will result two 15 like printed slips which may be used in manifolding.

It is necessary in this form of printing to have the two or more type plates in a perfect alignment and in case the alignment 20 should become distorted for any reason to have a quick guide for setting the said plates correctly in the chase again. It is also necessary that the spacing of the various lengthwise lines in each plate should 25 correspond.

It is the object of my invention to provide a device which can be used in connection with mounting boards or chases, and which not only serves as a guide to the press-man 30 in arranging his plates in the chase, but also holds the plates in the corrected alignment until the clamping blocks, nail fasteners, or the like in the chase may be completely and permanently adjusted.

35 These objects and other advantages to be noted I accomplish by that certain construction and arrangement of parts to be hereinafter more specifically pointed out and claimed.

40 In the drawings,

Figure 1 is a plan view showing the application of the guide bar or straight edge to a set of three manifolding form plates in a chase.

45 Figure 2 is a front view showing the straight edge device over a chase, and also (slightly separated) the clamping device.

Figure 3 is an elevation of a rack for mounting a series of standard straight 50 edges, as used in manifolding form printing.

Figure 4 is a detail side elevation of the clamping device.

Figure 5 is a detail of the slider.

I provide any sort of support 1, for my 55 device, which may be a flat wood or metal structure having side bars 2, 2. These side bars are formed with T-slots 3 for the clamping device, and with notched ribs 4 for the straight edge. The support will 60 also have a shoulder or rib 5 against which the chase may be set.

The straight edge comprises essentially a bar 6 having arranged along it a series of 65 pointers 7 which are carefully positioned so as to correspond with some standard printing arrangement, such as in this instance, for a given vertical line of the sections of manifolding paper. This bar is adapted to seat in the notches of the ribs 4 and thus to 70 be very accurately aligned across the bed.

On one end of the straight edge bar is a small clamp 8, which straddles the rib, i. e. slides upon it in any desired form of slider, 75 and is held on the bar by a screw so that it can be clamped down to the ribs on the support in desired position. This clamp may, of course, be duplicated for use on both ends of the straight edge. I have not shown it 80 in detail as any form of device can be used or the device omitted altogether.

The clamp for holding a chase down on the holder is constructed as follows: Standards 9, 9, are provided having a brace rod 10 between them, and T-headed bolts 11 85 engaging in the T-slots of the support and presenting threaded ends for reception of clamping nuts 12.

Pivotedly held in the standards is a rock shaft 13 having its ends 14 eccentric to the 90 body thereof, so that it acts as a cam.

The tie bar or brace rod 10 carries arms 15, 15, which extend to a point beneath the eccentrically mounted shaft. The arms 15 95 serve as the support for a mounting bar 16 and the arms are held rigidly on the rod 10, so as to hold the bar 16 against movement.

The clamp bar 17 has a series of pins or 100 posts 18 thereon, which extend upwardly through the mounting bar, and have heads 19 lying in the path of the eccentric shaft. Between the heads and the mounting bar are springs 20, which bear against bar 16 and thrust up the pins normally to hold the clamp bar away from clamping position. When, however, the shaft 13 is rocked by 105 its handle 21 it will contact with the heads of the pins and thrust them down, where-

upon the clamp bar will move to clamping position.

As so constructed, the operation of the device is as follows; reference being had to 5 a structure used with manifolding paper:—

The press-man arranges his printing plates 22 in a chase 23, and thrusts the chase into the support until it abuts against the back shoulder thereof. He then sets the straight

10 edge piece which is designed for his particular job and adjusts the plates in the chase until they are in exact alignment transversely, and until the various vertical lines of the separate plates are in exact correspondence with the arrows or pointers on the straight edge.

He then thrusts down the handle of the eccentric shaft and clamps the plates and the chase as well into fixed position, while

20 he tightens up on the various blocks and hooks that move in the chase for holding the printing plates.

There will be no shifting of the plates 25 during the tightening operation, due to the clamp, and any chance shift will be at once noted on the straight edge.

I have shown in Figure 3 an end view 30 of a support 1, which has legs 1^a, and at one end a rack 24. This rack is provided to support a variety of straight edges, all 35 of which are adapted for use with the support, but each of which has a different pointer arrangement and has been particularly designed for one of the standard kinds of work to be done.

This multiplication of straight edge pieces 40 I find of considerable economy of time as against having adjustable pointers which would have to be carefully set and subject to chance dislodgment.

I do not wish to be limited to the details 45 of construction above set forth, and do not wish my failure to mention various equivalent structures to be construed as a desire that my claims be limited in scope or application to the special form of device selected for purpose of illustration.

Having thus described my invention, what 50 I claim as new and desire to secure by Letters Patent, is:—

1. In a device for the purpose described, 55 a holder for a chase with printing plates therein or the like, an alignment guiding means supported on the holder, and a clamp also engaging the holder and adapted to engage the plates and hold them during tightening of them in the chase whereby the plates may be aligned while in the holder and then clamped to the holder and locked into the chase while clamped.

2. In a device for the purpose described, 60 the combination with a member on which a chase with printing plates therein or the like may be set, of adjustable alignment guiding means mounted on said holder and

held in juxtaposition to the plates on the chase, and a clamp also mounted on said holder and adapted to engage the plates in the chase during tightening of them in the chase whereby the plates may be aligned 70 while in the holder and then clamped to the holder and locked into the chase while clamped.

3. In a device of the character described, 75 the combination of an alignment guiding means, a support therefor and for a chase with printing plates therein, and means on the support to retain the plates in the chase in adjusted position during tightening of the fastening means of the chase thereon 80 whereby the plates may be aligned while in the support and then clamped to the support and locked into the chase while clamped.

4. In a device of the character described, 85 the combination of a support adapted to receive a chase with printing plates therein or the like, a straight edge adapted to engage the support and lie over the chase, and a clamping means on the support and adapted 90 to engage the plates in the chase to hold them in fixed position, for the purpose described whereby the plates may be aligned while in the support and then clamped to the support and locked into the chase while 95 clamped.

5. In a device of the character described, 100 a support comprising a portion to receive a chase, side bars extending along said portion, the side bars having channels therein, a clamp device having standards equipped 105 with engaging means in said channels, said clamp device having means adapted to come down against a chase in said portion, said engaging means being adapted to be secured in desired positions of fixed adjustment in said channels, and a straight edge mounted on said side bars whereby the locking of the plates in the chase can be accomplished while clamped with relation to the 110 straight edge.

6. In a device of the character described, 115 a support comprising a portion to receive a chase, side bars extending along said portion, the side bars having channels therein, a clamp device having standards equipped 120 with engaging means in said channels, said clamp device having means adapted to come down against a chase in said portion, said engaging means being adapted to be secured in desired positions of fixed adjustment in said channels, and a straight edge mounted on said side bars, said side bars having notches therein and said straight edge having means to engage in said notches whereby the locking of the plates in the chase can be accomplished while clamped with relation to the straight edge.

7. In combination with a support for a 130 chase or the like, a clamp mounted on the

- support to engage the face of devices in the chase, and a straight edge adapted to engage the support, said straight edge having pointers thereon interspaced to form a guide transversely of the guide provided by the straight edge whereby the plates may be aligned while in the support and then clamped to the support and locked into the chase while clamped.
- 5 10 8. A device for gaining quick alignment of type plates in a chase, comprising means to mount the chase, having aligning means positioned over the plates when mounted therein, and a clamp device comprising standards on the holding means, a bar suspended across between said standards, and an eccentric shaft in the standards to engage the bar.
- 15 9. A device for gaining quick alignment of type plates in a chase, comprising means to mount the chase, having guiding means
- 20
- therein for use in aligning the plates in the chase, and a clamp to hold the plates while being fastened tight in the chase, said clamp being in engagement with the chase mount- 25
10. A device for gaining quick alignment of type plates in a chase, comprising means to mount the chase, having guiding means therein for use in aligning the plates in the chase, and a clamp to hold the plates while being fastened tight in the chase, said clamp being in engagement with the chase mount- 30
- 35
- ing means, and comprising a pair of standards, means for supporting mounting plates between said standards, a clamp plate having pins thereon held under spring tension in the mounting plates, and cam means on the standards for engaging the said pins and thrusting them downwardly.

ALBERT W. METZNER.
